ATTACHING MEANS FOR ORNAMENTAL
DEVICES

Alfred S. Donaldson, Newark, N. J., and Roy
Milton Slipp, Leominster, Mass., assignors to
Dupont Viscocloid Company, Wilmington, Del.,
a corporation of Delaware

Application July 20, 1932, Serial No. 623,565

3 Claims. (Cl. 41—34)

This invention relates to the application of an ornamental device such as a medallion to an extended surface on a hairbrush or hand mirror or other toilet ware. The invention is also applicable to other articles having extended surfaces for ornamentation.

It is the general object of our invention to provide a medallion or ornamental device of improved construction, together with improved means for securing such a medallion or device to a surface to be ornamented. Preferably, the medallion or device is secured in a recess previously formed in the material of the surface to be ornamented.

The invention is particularly applicable to the ornamentation of objects made from cellulose nitrate, commonly known as "celluloid", but certain features of the invention are of more general application.

Our invention further relates to arrangements and combinations of parts which will be herein-after described and more particularly pointed out in the appended claims.

A preferred form of the invention is shown in the drawing, in which

Fig. 1 is a plan view of a hairbrush embodying our invention;

Fig. 2 is a sectional elevation, taken along the line 2—2 in Fig. 1 but with the medallion omitted;

Fig. 3 is an enlarged plan view of a medallion adapted for the carrying out of our invention;

Figs. 4 and 5 are detail sectional elevations, taken along the lines 4—4 and 5—5 in Fig. 3;

Fig. 6 is a bottom view of the medallion, ready for application to the supporting surface;

Fig. 7 is an enlarged fragmentary sectional elevation, also taken along the line 2—2 in Fig. 1;

Fig. 8 is a similar view of a slight modification, and

Figs. 9 and 10 are sectional views of additional modifications.

Referring to the drawing, we have shown our invention embodied in a hairbrush, preferably formed of sheet celluloid of substantial thickness, and having a body portion B and a handle H. The body B is shown in Fig. 2 as provided with a shallow recess 10 adapted to receive a medallion M.

The medallion M is preferably formed of thin sheet metal and is of arched or convex cross section, as clearly shown in Figs. 4 and 5. The convex or outer surface of the medallion may be coated with enamel or otherwise decorated as may be desired.

In the carrying out of our invention, we provide a layer 12 of thin foraminous material, such

as fine-mesh woven wire cloth or finely perforated metal, which material is cut roughly to the outline of the medallion, as indicated in Fig. 6, and is firmly secured to the under or concave side of the medallion in some convenient manner, as by applying spaced portions 14 of solder thereto. Preferably the layer 12, when thus applied, is spaced from the middle portion of the medallion M, as clearly indicated in Fig. 7, and is also positioned above the outer lower edge 15 of the medallion.

Having prepared a medallion or ornamental device as above described, the recess 10, or the under side of the medallion M, or both are given a substantial coating of a semi-liquid celluloid cement or other cementing material. The parts are then assembled as indicated in Fig. 7, the medallion M closely fitting the recess 10 and being pressed firmly into said recess. The parts are then allowed to stand in assembled relation until the cement has set, after which the medallion will be found to be very securely attached to the surface to be ornamented, and to be removable therefrom only with considerable difficulty.

Obviously the recessing of the surface to be ornamented may in some cases be omitted, and the medallion M may be directly secured to a continuous extended surface, as shown in Fig. 8. Preferably, however, the surface is recessed in most cases to receive the medallion or other ornamental device.

While we have shown and described our invention in Figs. 3 to 8 as applied to an arched or convex medallion, the invention may also be applied to a flat medallion or ornamental device as indicated at 20 in Fig. 9. In this case the wire mesh fabric 21 is preferably spaced slightly downward or away from the device 20, so that it may be firmly embedded in the cementing material. With this construction, it is also desirable to provide a recess having an outer portion 22 and an inner portion 23, thus providing a shoulder or support for the device 20.

In Fig. 10 we have shown our invention applied to a medallion or ornamental device 30 having a concave outer surface and having wire fabric 31 secured to the under and convex side thereof and preferably slightly spaced therefrom. The medallion 30 may be inserted in a double recess of the type shown in Fig. 9 or the bearing shoulder 105 33 may be formed to fit the under surface of the concave medallion as shown in Fig. 10.

Having thus described our invention, it will be seen that we have provided a very simple and inexpensive means of securing a medallion or

2

other ornamental device to an object having a surface to be ornamented, and the medallion or device thus secured will be found to be effectively held against accidental displacement.

5 Having thus described our invention and the advantages thereof, we do not wish to be limited to the details herein disclosed, otherwise than as set forth in the claims, but what we claim is:—

1. In an article of toilet ware or other article having a surface to be ornamented, an ornamental device having a layer of thin foraminous material secured across the under side thereof, and cementing material securing said layer and device to said article to be ornamented, said article being recessed to receive said ornamental device and being provided with a deeper central recess to receive said foraminous layer and cementing material, and said cementing material enveloping said foraminous layer and filling the openings therein and also firmly adhering to the material of the article to be ornamented.

2. As an article of manufacture, an ornamental medallion formed of thin sheet metal recessed and arched in cross section, a sheet of fine-mesh woven wire fabric positioned underneath and within the recess of said medallion but spaced therefrom in its central portion, and means to secure edge portions of said wire fabric to edge portions of said medallion.

3. An article of toilet ware, having a surface to be ornamented and having a recess therein, an ornamental medallion fitting said recess and made of thin sheet metal outwardly arched in cross section, a layer of fine wire screen fitting within the medallion and secured thereto but spaced from the underside thereof, and cementing material applied in said recess and enveloping the wires of said screen layer, whereby said medallion is firmly retained in said recess and against displacement from said article.

ALFRED S. DONALDSON.
ROY MILTON SLIPP.
